UNITED STATES PATENT OFFICE

STEPHEN L. TINGLEY, OF BOSTON, MASSACHUSETTS, ASSIGNOR TO SMELTERS, REFINERS & CHEMICALS CORPORATION, OF NITRO, WEST VIRGINIA, A CORPORATION OF VIRGINIA.

ELECTRIC FURNACE.

Application filed December 13, 1920. Serial No. 430,114.

To all whom it may concern:

Be it known that I, STEPHEN L. TINGLEY, a citizen of the United States, residing at Boston, county of Suffolk, State of Massachusetts, have invented an Improvement in Electric Furnaces, of which the following description, in connection with the accompanying drawing, is a specification, like characters on the drawing representing like parts.

This invention relates to electric furnaces and particularly to furnaces of that type that are constructed to produce a circular or hollow arc and in which the material to be treated is delivered into the center of the arc.

One of the objects of the invention is to provide an electric furnace of the above type which is constructed so that the material to be smelted or otherwise treated is delivered into the middle of an annular arc, or in other words, is delivered into a space which is entirely surrounded by an arc.

Another object of the invention is to provide an improved electric furnace of this type in which the hollow electrode not only provides a channel through which the material to be treated is delivered to the hollow annular arc but also acts as a means for pre-heating the material as it is being delivered to the arc.

Still another object of the invention is to provide an electric furnace of this type in which one of the electrodes is provided with passages through which gases that are formed at the arcing point may escape.

Still another object of the invention is to provide an improved electric furnace of the above type which has a series of circular or hollow arcs by means of which the material can be more economically treated.

Another object of the invention is to provide an improved electric furnace by which the smelting operation may be greatly facilitated, thus enabling the furnace to treat material faster than can be done in furnaces as heretofore constructed.

Other objects of the invention are to provide an improved means of supporting and adjusting the electrodes and otherwise improving electric furnaces, all as will be more fully hereinafter set forth.

In order to give an understanding of my

invention, I have illustrated in the drawings a selected embodiment thereof which will now be described after which the novel features will be pointed out in the appended claims.

In the drawings, the figure is a vertical section of a furnace embodying my invention.

The two terminals between which the arc is formed are indicated at 1 and 2, respectively. These terminals may be made of carbon or any other suitable material. The electrode 1 is provided at its end with a circular crater 3 and with a central peak for the protuberance 4. The electrode 2 is provided with a central passageway or conduit 5 through which the material to be smelted is fed to the arcing point, and it is formed on its lower end with a circular groove 7 that forms an annular ridge 6 surrounding the protuberance 4, and also an annular portion 8 adjacent the peripheral portion 9 of the electrode 1 that is situated outside of the crater 3. The electrode 1 is connected to a source of electricity by a suitable cable 10, and the electrode 2 is also connected to said source of electricity by a cable 11. With this construction there will be an annular arc formed between the peak 4 and the annular ridge 6, and a circular arc formed between the circular portions 8 and 9 of the electrodes.

The material which is delivered through the conduit 5 passes first through the arc existing between the ridge 6 and the peak 4, and as it becomes melted it accumulates in the crater 3. The electrode 1 is provided with one or more tap holes 12 leading from the crater 3, these tap holes communicating with spouts 13 through which the molten material may be delivered to any suitable receptacle.

The arc formed between the portions 8 and 9 of the electrodes is situated exterior to the crater, and this arc not only assists in melting the material in the crater which may not have been melted by the inner arc, but it also prevents any material from escaping from the crater through the space between the electrodes.

I have illustrated herein electrodes constructed to provide two concentric arcs, but the number of concentric arcs is immaterial

and the electrodes might be arranged to produce more than two arcs without departing from the invention.

These electrodes may be supported in any suitable way. The electrode 1 is shown as having its lower end enclosed in a housing 14 of insulating material and as being supported on the upper end of an adjusting screw 15 which has screw-threaded engagement with a nut 16 that is supported on a rest or plate 17. The nut 16 is in the form of a bevel gear which meshes with a bevel gear 18 carried by a shaft 19, the latter having a crank 20 by which it may be turned. This shaft 19 is journaled in a bearing 21 that is carried by the plate 17. With this construction the turning of the shaft 19 will operate to rotate the nut 16 in one direction or the other thereby raising or lowering the electrode 1, thus providing for its proper adjustment as well as furnishing it a suitable support. The supporting plate 17 is shown as sustained on buffer springs 22, the purpose of which is to give a resilient support to the electrode 1, thereby to prevent any injury due to a kicking action of the electrode when the electricity is turned on.

The lower end of the electrode 1 is shown as being suitably guided in a stationary curb 20 or wall 23. The electric cable 10 is shown as connected to a copper plate 24 which is secured to the end of the electrode 1 thereby making a good electrical contact.

The upper electrode 2 is adjustably supported so that it may be readily adjusted vertically, and is also so supported that it may be readily removed in order to be replaced by another electrode. This electrode has secured to its upper end a copper plate 25 to which the cable 11 is attached, thus making the proper electrical connection. The electrode is also secured in a supporting ring 26 which encircles the upper end thereof and which is adjustably suspended from brackets 27 that project from the walls of a housing 28 that forms the wall of the furnace. For this purpose the supporting collar 26 is provided with two arms 29 through which are screw-threaded adjustable supporting screws 30 that in turn are swiveled in the brackets 27, said screws having heads 31 by which they may be turned and which also serve by their engagement with the brackets 27 to support the screws. The turning of the screws in either direction will raise or lower the electrode 2 and by this means the electrode can be maintained in its proper adjusted position. The adjusting screws 30 provide means for making a limited adjustment of the electrode 2 in a vertical direction.

I have also provided other means by which the electrode may be removed from the furnace and a new electrode inserted in position. This other means is in the form

of one or more blocks and tackle 32, one block 33 of each block and tackle being connected to the plate 25, and the other block 34 of each block and tackle being connected to the top 35 of the housing 28. By this means 70 the electrode 2 may be raised entirely away from the electrode 1, thus facilitating the installation of a new electrode or the removal of an old one.

The casing 28 of the furnace is formed 75 with a bridge wall 37 which is situated above the arcing point and which supports a suitable guide for the electrode 2. This guide is herein shown as comprising an inner cylindrical member 38 of crucible clay 80 through which the electrode 2 passes, and an outer shell 39 of some suitable material, such, for instance, as ordinary tile pipe, the space between the outer shell 39 and the inner member 38 being filled with asbestos 85 wall, as shown at 40.

The space 41 beneath the bridge wall will be of sufficient size to accommodate the operator or operators who have charge of the furnace, and in order to protect such workmen from the arc, I propose to employ a circular shield 36 of some non-fusible material which encloses the arcing point. This shield 36 is in the form of a cylinder of the proper size and it is shown as adjustably supported so that it can be raised or lowered. When in operative position the upper end thereof will come either against the bridge wall or the supporting guide for the upper electrode. This shield 36 is shown as carried by a collar 42 which has arms 43 extending therefrom, each arm having swiveled therein an adjusting screw 44 that has screw-threaded engagement with a supporting arm or bracket 45 carried by the casing 28. This shield 36 is provided with suitable openings 46 to receive the sockets 13. My improved furnace is provided with means for taking care of any gases that may be generated during the operation of the furnace and thereby preventing such gases from accumulating in the space 41 occupied by the operator. For this purpose I provide a pipe or conduit 47 which leads to a suitable blower or suction apparatus (not shown) and which communicates with the interior of the casing 28. Any gases, therefore, which accumulate in the casing 28 are drawn off through the pipe 48, 47. The operation of melting the material at the arcing point results in the production of certain gases, and to provide for the disposal of such gases, I propose to make the electrode 2 with a plurality of ducts 48 which lead into the groove 7 and which extend longitudinally through the electrode and communicate at their upper end with pipes 49 that lead into the pipe 47. The suction produced in the pipe 47 will operate to draw any gases up through the ducts 48 and pipes 49. I have 120

125 110 115 125 130

130

130

also provided a pipe 50 which extends through the bridge wall 37 and into the pipe 47, so that the suction in the pipe 47 will result in withdrawing from the space 41

5 any gases that may accumulate therein. With this construction, therefore, the space occupied by the operator will be at all times free from obnoxious or disagreeable gases.

The material to be treated is delivered to 10 the conduit 5 through a delivery pipe 51 which extends up through the top of the casing 28 and communicates with a suitable hopper 52. This type of furnace is usually used in treating granular material and in 15 operating the furnace it is simply necessary to keep the hopper 52 filled with the granular material, the latter gravitating through the pipe 51 and conduit 5 to the arcing point as the material is melted and drawn off 20 through the tap holes 12. The electrode 2 becomes quite hot during operation and thus it acts as a means for pre-heating the material while in the conduit 5. This pre-heating of the material will oftentimes result 25 in the formation of gases, and to provide for eliminating these gases, I employ a pipe 53 which extends longitudinally of the pipe 51 and is open at its lower end, and the upper end of which leads through the 30 pipe 51 into the pipe 47. The suction in the pipe 47 will, therefore, draw out of the conduit 5 any gases that may be formed therein by the pre-heating operation. The pipe 51 is also formed with vent openings 35 54 that lead directly into the pipe 47, and these vent openings, together with the pipe 53 serve to prevent the accumulation of any gas in the delivery pipe 51.

I claim:

40 1. A pair of electrodes for an electric furnace, one of said electrodes having a shape relative to the other such as to produce a plurality of concentric annular arcs.

2. A pair of electrodes for an electric furnace, one of said electrodes having at its 45 arcing end a plurality of annular ridges and the other electrode having its arcing end shaped to co-operate with said ridges to produce a plurality of concentric annular arcs.

3. A pair of electrodes for an electric furnace, one of said electrodes having a central 55 passage and a plurality of ridges at its arcing end and the other electrode having a shape to co-operate with said first-named electrode to produce a plurality of annular arcs.

4. In an electric furnace, the combination 60 with two electrodes, one of which is tubular and the other of which has a protuberance projecting slightly into the bore of the tubular electrode, of means to deliver the material to be treated to the arc through the tubular electrode, and the relation of the electrodes at the arcing point being such as to

retard the passage of the material through the tubular electrode whereby the material will remain in the latter for a length of time and thereby become preheated.

5. A pair of electrodes for an electric furnace, one of said electrodes having a passage therethrough for the delivery of material to the arc and also having other passages therethrough for the escape of gases formed at the arcing point. 75

6. A pair of electrodes for an electric furnace, one of which has a passage therethrough for the delivery, to the arc, of the material to be treated and also other passages therethrough for the escape of gases 80 produced at the arc.

7. A pair of electrodes for an electric furnace, one of said electrodes having a protuberance on its end and the other having a central bore or opening of large diameter 85 than the protuberance.

8. A pair of electrodes for an electric furnace, one of which is tubular and the other of which has a protuberance on its end surrounded by an annular groove. 90

9. A pair of electrodes for an electric furnace, the upper electrode being tubular and the lower electrode having a central protuberance and an annular depression in its upper face surrounding the protuberance 95 and constituting a puddling bed.

10. A pair of electrodes for an electric furnace, the upper electrode having a central passage therethrough for the delivery of material to the arcing point and the lower electrode having a protuberance and an annular depression surrounding the protuberance and forming a puddling bed, 100 said electrodes being constructed to produce a circular arc surrounding the puddling bed. 105

11. In an electric furnace, the combination with two electrodes, of means to support the same, the lower electrode having an annular depression forming a puddling bed, said upper electrode having a central channel through which material to be treated is delivered to the arc, and said electrodes being so constructed as to produce an annular arc surrounding the puddling 110 bed and another annular arc inside the puddling bed and through which the material passes as it is delivered to the bed. 115

12. A pair of electrodes for an electric furnace, the lower electrode having an annular depression forming a puddling bed, and a cone-shaped protuberance situated centrally of said puddling bed, and said electrodes being constructed to produce an annular arc surrounding the puddling bed and another annular arc centrally of said bed. 120 125

13. A pair of electrodes for an electric furnace, the lower electrode having in its upper face a central protuberance and an 130

- annular depression constituting a puddling bed surrounding the protuberance, said electrodes being constructed to produce an annular arc surrounding the puddling bed, 5 said lower electrode having tap holes situated to discharge through said annular arc.
14. A pair of electrodes for an electric furnace, the upper electrode having in its lower end an annular groove and being provided with one or more gas vents leading from said groove.
15. In an electric furnace, the combination with a pair of electrodes, of resilient means for yieldingly supporting the lower 15 electrode.
16. In an electric furnace, the combination with a pair of electrodes, of means for raising and lowering the lower electrode and resilient means providing at all times 20 a resilient support for said electrode.
17. In an electric furnace, the combination with a pair of electrodes, of a cylindrical jacket of fire-clay or other heat resisting material closely surrounding the central 25 portion of the upper electrode and insulating the latter against heat radiation.
18. In an electric furnace, the combination with a pair of electrodes, of a cylindrical jacket of heat resisting material surrounding the central portion of the upper electrode, and a packing of asbestos exterior to and surrounding said jacket.
19. In an electric furnace, the combination with a furnace structure or casing, of 30 a bridge wall within the same, a pair of electrodes, the upper one of which is provided with a feed conduit and extends through said bridge wall and a heat-insulated jacket sustained by said bridge wall 35 and surrounding the upper electrode.
20. In an electric furnace, the combination with a furnace housing, of a bridge wall within said housing forming beneath it an operating chamber, a pair of electrodes with- 40 in the housing and arranged so that the
- arcing point is within said operating chamber, the upper electrode having a feed conduit therethrough.
21. In an electric furnace, the combination with a furnace housing, of a bridge 50 wall within said housing forming beneath it an operating chamber, a pair of electrodes within the housing and arranged so that the arcing point is within said operating chamber, and a gas vent extending through said bridge wall permitting the escape of gas from said chamber, one of said electrodes having a feed conduit through which material is fed to the arcing point.
22. A pair of electrodes for an electric 55 furnace, one of said electrodes having means for preheating the material delivered to the arcing point and also having gas vents leading from the arcing point.
23. A pair of electrodes for an electric 60 furnace, said electrodes being constructed to produce a hollow arc and one of the electrodes having a passage to deliver material to the arcing point and gas vents leading from the arcing space.
24. In an electric furnace, the combination with two electrodes, one of which has a channel therethrough for the delivery of material to the arcing space, and a gas vent 65 leading from the upper end of said channel for the purpose of taking off gas which generates in said channel.
25. In an electric furnace, the combination with a pair of electrodes, one of which is provided with a channel for the delivery 70 of material to the arcing space, one or more gas vents leading from the arcing space, a gas vent leading from the upper end of said channel, and a conduit leading to a stack and with which all gas vents communicate.
- In testimony whereof, I have signed my name to this specification.

STEPHEN L. TINGLEY.
